AUTOMOBILE ORNAMENT

Wallace H. Hawkins and Homer Hawkins,
Panama City, Fla.

Application September 26, 1952, Serial No. 21,604

Term of patent 14 years

(Cl. D14—30)

To all whom it may concern:

Be it known that we, Wallace H. Hawkins and Homer Hawkins, both citizens of the United States and residing at Panama City, Bay County, Florida, have invented a new, original, and ornamental Design for an Automobile Ornament, of which the following is a specification, reference being had to the accompanying drawing forming part thereof.

In the drawing—

Fig. 1 is a side view of an automobile ornament, showing our new design;

Fig. 2 is a rear view thereof; and

Fig. 3 is a cross-sectional view taken on line 3—3 of Fig. 2.

The dotted line showing in Fig. 1 is for illustrative purposes only.

We claim:

The ornamental design for an automobile ornament, as shown and described.

WALLACE H. HAWKINS.
HOMER HAWKINS.
